LOCK

Herbert H. Rauh, Columbus, Ohio

Application August 27, 1940, Serial No. 354,388

12 Claims. (Cl. 70—364)

This invention relates to locks, and refers to cylinder type tumbler locks particularly.

As is well known, many attempts have been made in the past to increase the surety of locks of this type against picking. This invention likewise is directed toward improvement in this respect, and to this end, has as one of its objects to provide a lock so designed that the cylinder may be forcibly turned a limited extent out of its normal locked position as in an attempt to pick the lock so as to disalign the tumbler receiving openings of the cylinder and its casing, and thereby preclude jarring the tumblers to their unlocking positions.

Another object of this invention is to provide a lock of the character described wherein at least one of the mutually engageable surfaces of the tumbler and its openings is resilient to permit a limited degree of forced rotation of the cylinder.

More specifically, it is an object of this invention to provide a lock of the character described wherein rubber or a similar material is utilized to provide the necessary resiliency at the abutting surfaces of the tumblers and their openings to allow limited forced rotation of the cylinder.

With the above and other objects in view which will appear as the description proceeds, this invention resides in the novel construction, combination and arrangement of parts substantially as hereinafter described, and more particularly defined by the appended claims, it being understood that such changes in the precise embodiment of the herein disclosed invention may be made as come within the scope of the claims.

The accompanying drawing illustrates several complete examples of the physical embodiment of the invention constructed in accordance with the best modes so far devised for the practical application of the principles thereof, and in which:

Figure 1 is a cross sectional view through a conventional pin type tumbler lock, illustrating the application of this invention thereto;

Figure 2 is a view similar to Figure 1, illustrating how limited forced rotation of the cylinder is permitted to guard against picking of the lock;

Figure 3 is a view similar to Figure 1, illustrating a slightly modified embodiment of the invention;

Figure 4 is a longitudinal sectional view through the lock shown in Figure 3;

Figure 5 is a perspective view, illustrating another manner of constructing the tumblers

for the locks shown in Figures 1 to 4, inclusive; and

Figure 6 is a cross sectional view through a flat plate type tumbler lock, illustrating the application of this invention thereto.

Referring now particularly to the accompanying drawing in which like numerals indicate like parts, the numeral 5 designates the mounting member or casing of a pin type tumbler lock, which has a bore 6 to receive a cylinder 7. The mounting member or casing also has a plurality of radial bores 8 opening to the bore 6 for the reception of pin tumblers 9. These tumblers are yieldingly projected into the bore 6 by springs 10 and when the cylinder is in its locked position of rotation and a key is not in place therein, the tumblers are projected by their springs into radial bores 11 in the cylinder. The pin tumblers in this position extend across the line of parting between the cylindrical surface of the cylinder and the casing bore, and thus secure the cylinder against turning.

The openings 11 communicate with a keyway 12, as is customary, into which a proper key 13 may be inserted to lift drivers 14 slidably mounted in the openings 11. The drivers 14 are of such lengths that when a properly bitted key is inserted, the junctures of all of the tumblers and their drivers are on the line of parting between the cylinder and the casing bore so that the cylinder is free to be turned.

Ordinarily, the tumblers and their drivers are formed from round metal stock and have a fairly snug sliding engagement in their respective openings. With such conventional construction, the lock could be picked by means of a picking tool insertable into the keyway to vibrate the drivers while a turning force is constantly maintained on the cylinder by an instrument inserted into the mouth of the keyway, this being possible by virtue of the fact that as the tumblers are jarred to their unlocked positions, the twist on the cylinder would be sufficient to dispose a shoulder under the tumbler and prevent its return to locking position.

With the present invention, this scheme of picking the lock is entirely precluded for the instant a turning force is applied to the cylinder, as is done at the initiation of an attempt to pick the lock, the tumbler openings of the cylinder and casing are disaligned, as illustrated in Figure 2. This is made possible by the fact that the mutually engageable surfaces between the tumblers and their bores, or at least one of them, is resilient.

In the embodiment of the invention illustrated in Figures 1 and 2, this resiliency is afforded by encircling the tumblers 9 and their drivers 14 with a substantial layer of rubber 15, the tumblers and the drivers preferably having their metal body portions of spool-shape with the rubber portions positioned between the ends thereof. With this construction, as will be readily apparent from Figure 2, the cylinder may be forcibly turned out of its normal position, and thereafter, jarring of the tumblers to unlocked positions is impossible.

The desired resiliency may also be obtained by providing the mounting member or casing and the cylinder with compressible inserts 16 and 17, respectively, as shown in Figures 3 and 4. In this instance, the casing and the cylinder have their tumbler receiving bores 8 and 11, respectively, opening to elongated recesses 18 and 19, respectively, in which the inserts 16 and 17 are secured. These inserts have bores which align with and continue the tumbler receiving bores 8 and 9.

With this construction, the tumblers and their drivers may be of solid metal, as in the conventional pin tumbler locks, or the same construction as illustrated in Figures 1 and 2 may be employed wherein the medial portions of the tumblers and their drivers have their outer wall surfaces resilient.

While it is desirable to have the end portions of the tumblers and drivers which engage each other, metal for their entire diameter, a construction such as illustrated in Figure 5 may be employed wherein the rubber collar 20 extends directly to one end of the tumbler or driver.

In the case of flat plate tumbler locks, such as illustrated in Figure 6, the invention is applied either by providing resilient inserts in the casing 21 or on the tumblers 22, or both, as illustrated in Figure 6. In this type of lock, as is well known, the cylinder carries a plurality of plate tumblers 22 yieldingly urged by individual springs 23 to project one end thereof into a tumbler receiving groove 24 in the mounting member or casing. The insertion of a properly bitted key retracts all of these plate tumblers within the lock cylinder and frees the cylinder for rotation.

To enable a limited degree of forced rotation in this construction, the walls of the tumbler receiving grooves 24 may be formed by rubber inserts 25, or the side edges of the tumblers 22 may have inserts 26 applied thereto. In the construction shown, both of these expedients are utilized, but it will be readily appreciated that either one alone would suffice.

In all instances, the rubber used is of a semi-soft variety and is secured in position by being vulcanized to its carrying part or by any other suitable method.

From the foregoing description taken in connection with the accompanying drawing, it will be readily apparent to those skilled in the art that this invention provides a cylinder type tumbler lock which cannot be picked in the conventional manner by virtue of the fact that it permits a degree of forced rotation of the cylinder so as to disalign the tumbler openings in the cylinder and casing, and thereby preclude jarring the tumblers to an unlocking position.

What I claim as my invention is:

1. In a lock having a bored mounting member and a lock cylinder movable therein: a tumbler carried by the cylinder and engageable with the mounting member to hold the same against

movement, said tumbler having a resilient portion located to engage the mounting member in the normal position of the tumbler so that a degree of movement is permitted the cylinder while the tumbler is in its operative position.

2. A lock of the character described in which relatively movable parts are secured against relative motion by key controlled tumblers which extend across the line of parting between said parts, the portion of the surface of each tumbler which extends across the line of parting between said parts being resilient.

3. A lock of the character described in which relatively movable parts are secured against relative motion by key controlled tumblers which extend across the line of parting between said parts, the portion of the wall of the tumbler opening in one of said parts being resilient adjacent to the line of parting between said parts.

4. In a lock of the character described: a casing member having a bore; a cylinder member in the bore, said members having openings adapted to be aligned so that the wall surfaces of the openings form substantially continuations of each other; a tumbler movable in said openings and positionable across the line of parting between the cylinder and the bore with its wall surfaces in sliding engagement with the wall surfaces of the openings, and one of said wall surfaces being resilient to allow limited relative motion between said members.

5. In a lock of the character described: a casing member having a bore; a cylinder member mounted therein, said members having tumbler openings adapted to be aligned; tumblers movable in said openings and positionable across the line of parting between the cylinder and casing members, and said tumblers having resilient outer surfaces to engage the surfaces of the tumbler openings so that a limited degree of forced relative motion between said members is possible.

6. In a lock of the character described: a casing member having a bore; a cylinder member mounted therein, said members having openings adapted to be aligned; a tumbler movable in said openings and positionable across the line of parting between the members, and one of said members having the wall of its opening adjacent to the line of parting resilient so that a degree of relative motion between said members may be forcibly effected.

7. In a lock of the character described: a casing member having a bore; a cylinder member mounted therein, said members having openings adapted to be aligned; a tumbler movable in said openings and positionable across the line of parting between the members, and both of said members having the wall of their openings adjacent to the line of parting resilient so that a degree of relative motion between said members may be forcibly effected.

8. In a lock of the character described: a member having a tumbler receiving opening; a tumbler movable in said opening, said tumbler and the tumbler opening having wall surfaces adapted for mutual contact, and one of said surfaces being resilient.

9. In a lock: a casing member having a bore; a cylinder member movable in the bore; said casing member having a tumbler receiving opening communicating with its bore; a tumbler carried by the cylinder and projectible into said opening, said tumbler and the tumbler opening having mutually engageable surfaces, and one of said surfaces

being resilient so that a degree of relative motion between said members may be forcibly effected.

10. In a lock of the character described: a casing member having a bore; a cylinder member mounted therein; a tumbler receiving opening in one of said members; a tumbler carried by the other of said members and projectible into the tumbler receiving opening so as to extend across the line of parting between said members, said tumbler and the tumbler receiving opening having mutually engageable surfaces, and one of said surfaces being resilient.

11. In a lock of the character described: a casing member having a bore; a cylinder member rotatable in the bore; the casing member having a plurality of tumbler receiving openings communicating with its bore; the cylinder member having openings adapted to be aligned with the tumbler receiving openings; tumblers slidable in

said casing member openings and projectible into the cylinder member so as to extend across the line of parting between said members, and said tumblers having resilient outer surfaces at their portions which extend across the line of parting so that the cylinder member may be forcibly turned a limited amount.

12. A pin type tumbler lock in which the cylinder mounted in a casing bore is held against turning by spring propelled tumblers projectible into the cylinder, and wherein key operable drivers lift the tumblers to free the cylinder for rotation, the tumblers or the walls of the openings in which they are received being resilient adjacent to the line of parting between the cylinder and the casing so as to enable a degree of forced rotation of the cylinder in the casing.

HERBERT H. RAUH.
